ELECTROLYTIC CAN TREATING MACHINE

Paul E. Pearson and Alfred Treff, Chicago, Ill.,
assignors to Continental Can Company, Inc.,
New York, N. Y., a corporation of New York

Application August 5, 1942, Serial No. 453,704

7 Claims. (Cl. 204—200)

1

This invention relates to apparatus for treating receptacles such as cans by electrolysis and more particularly to apparatus especially adapted for the treating of the interior surfaces of cans or similar receptacles. An object of the invention is to provide a novel and improved apparatus for performing such treatments.

It is known that in the packaging of certain foodstuffs in metallic receptacles, e. g. cans, unsightly and objectionable staining of interior surfaces of the receptacles results during the conventional processing of the filled and sealed receptacles, this objectionable condition being termed sulphur-staining. It has been discovered that the sulphur-staining may be prevented by immersing the receptacles, prior to use, in an electrolytic bath comprising a solution of a metallic salt and alkali in water, and passing an electric current through the bath and the receptacles with the latter serving as electrodes. In our copending application Serial No. 453,703, filed August 5, 1942, there is disclosed and claimed a machine adapted for electrolytic treatment of the end closures of metallic receptacles, particularly the end closure surface portions to be presented internally. By the present invention we have provided a machine more especially adapted for performing the electrolytic treatment of the interior surfaces of cans or other receptacles which may include can bodies and articles having one end closed, the cans or receptacles however being open at one end during the treatment. The specific composition of the electrolyte forms no part of the present invention, and although machines embodying present invention are primarily intended for performing treatments to eliminate sulphur staining, they may also be adapted for other uses, such as electroplating or surface cleaning.

A machine constructed in accordance with the invention preferably includes a rotatable treating turret equipped at circumferentially spaced stations with means for supporting cans to be treated. Rotatable with the turret and associated with the can supports at the respective stations are means for filling the cans with electrolyte, moving electrodes relatively into the cans and establishing and maintaining for a predetermined period an electric circuit through the electrode, the electrolyte and the can at each station, and then withdrawing the electrodes relatively from the associated cans.

Another object of the invention is to provide a machine of the character stated including means for completely filling the cans with electro-

2

lyte so as to apply and maintain electrolyte in contact with the entire inside surface of the can, without however permitting electrolyte to overflow onto the outside surface of the can.

Another object of the invention is to provide a machine of the character stated including means for delivering to the cans measured charges of greater volume than the individual can capacities, and means for retaining the surplus electrolyte above the filled cans to thus assure complete filling of the cans.

Another object of the invention is to provide a machine of the character stated including means for moving electrodes into the electrolyte in the cans and then relatively withdrawing the electrodes in timed relation to the filling of the cans and the passing of an electric current through the cans and the electrolyte therein.

Another object of the invention is to provide a machine of the character stated including means for inverting the cans after their treatment to dump the electrolyte therefrom.

Another object of the invention is to provide a machine of the character stated for rejecting any can which has not been given a proper electrolysis treatment due either to failure to fill the can completely with electrolyte or failure of the electrolysis circuit.

Another object of the invention is to provide a container for measuring charges of treating fluid including an insert which may be removed and replaced by an insert of different displacement for varying the net or resultant capacity of the measuring container.

Another object of the invention is to provide a machine of the character stated including novel and improved means for washing the cans after the electrolysis treatment to remove electrolyte droplets which may adhere after inverting of the cans to dump the electrolyte.

Another object of the invention is to provide a machine of the character stated including means automatically operative during the electrolysis treatment for reversing the polarity of the electrolysis current or circuit.

Another object of the invention is to provide a machine of the character referred to including a compact arrangement of means for moving containers in a circuitous path at one level for being subjected to electrolysis treatment, and means for moving treated containers in a similarly circuitous path at a lower level below the treating path for being washed.

A further object of the invention is to provide a machine of the character referred to including

driving connections and timing devices for effecting operation of the parts to treat successively a steady stream of cans fed to and then discharged from the machine.

With these and other objects in view, which will appear more fully, the invention will be clearly understood from a reading of the following description, the appended claims, and the accompanying drawings.

In the drawings:

Figure 1 is a front elevation of a machine embodying the invention, some parts being broken away and others being omitted in order to enable the illustrated parts to be seen more clearly.

Figure 2 is a vertical section taken substantially through the center of the machine and at right angles to Figure 1.

Figure 3 is a view partly in top plan and partly in horizontal section, showing parts for feeding cans to stations on the revolving treating turret and for removing treated cans from the turret.

Figure 4 is a view partly in top plan and partly in horizontal section of machine parts at a level below the level of the parts shown in Figure 3, the lower level parts including washing equipment and means for discharging treated and washed cans from the machine.

Figure 5 is a view partly in elevation and partly in vertical section showing can inverting and can rejecting mechanism on an enlarged scale.

Figure 6 is a view partly in elevation and partly in vertical section showing the can conveying and inverting chain and driving mechanism therefor on an enlarged scale.

Figure 7 is a view partly in top plan and partly in section showing details of a reduction gear unit and overload cutoff switch operating mechanism.

Figure 8 is a detail elevational view of a pipe and nozzle for supplying electrolyte.

Figure 9 is a detail sectional elevation of the collector ring, brush equipment and detector control mechanism, drawn on an enlarged scale.

Figure 10 is a fragmentary vertical section drawn on an enlarged scale and showing equipment at one treating station for moving a can into position to be treated, filling it with electrolyte, and lowering an electrode into the can.

Figure 11 is a diagrammatic comparative development of a pair of collector rings, an electrode lowering and raising cam, and a can support raising and lowering cam shown associated to illustrate the timing of movement of the parts.

Figure 12 is a diagrammatic showing of an electrolyte supplying and recirculating arrangement; and

Figure 13 is an electric wiring diagram.

In its general nature the apparatus shown as embodying the invention in a preferred form includes a frame A comprising a base 1 and a plurality of standards 2 extending upwardly from the base and supporting a cover 3. A pedestal or thrust bearing 4 carried by the base 1 supports the lower end of a main or centrally disposed shaft 5 journaled also in bearings 6 and 6a. (See Figure 2.)

The shaft 5 carries for rotation therewith a traveling carrier or turret B adapted to move cans shown at X in a predetermined circular path during their treatment by electrolysis, and a turret C disposed at a level below the level of the turret B and also arranged to move cans over a circular path for being rinsed or washed to remove electrolyte which may have adhered

to the cans after their removal from the turret B.

Shortly after each can begins its movement on the turret B it is filled with a charge of electrolyte supplied from a measuring pocket or container 7 carried by a spider D keyed to the shaft 5 at a level above that of the turret B. A retractible electrode 8 is then lowered into the electrolyte in the can and an electric circuit is caused to be completed through the electrode 8, the electrolyte in the can and the can. The spider D carries a plurality of separate units each including a measuring pocket 7, an electrode 8 and mechanism for delivering the electrolyte from the pocket 7 into the can, for lowering the electrode 8 into the can and then removing it following the electrolysis treatment.

The equipment for treating the cans X by electrolysis is carried on the turret B and spider D, there being a plurality of circumferentially spaced treating stations which move around the shaft 5. Each station includes means for supporting the cans on the turret B, means including a measuring pocket 7 and electrode 8 mounted on the spider D, and other parts to be described hereinafter. The treatment is carried on at the several stations while the cans are being moved by rotation of the turret B, and after the treatment of each can has been completed the associated electrode 8 is raised and the can is removed from the turret B and deposited with its charge of electrolyte upon an endless conveyor chain 9. The chain 9 moves the cans past a rejection wheel 10 which is operated automatically to displace from the chain 9 any can which has not contained a full charge of electrolyte while being treated or any can during the treatment of which the supply of current may have failed.

The chain 9 moves along a substantially horizontally upper path and then downwardly and along a lower path so that cans held on the chain will be inverted in passing from the upper to the lower chain bath, thereby dumping the electrolyte into a suitably positioned receptacle from which the electrolyte is recirculated to the supply for the measuring pockets 7. See Figure 1. The empty cans are then moved in succession to the washing or rinsing turret C which carries them in inverted position along a circular trackway comprising spaced tracks 11-11. While being moved over the trackway the cans are subjected to washing or rinsing water sprayed from upper spray pipes 12 and lower spray nozzles 13. After having completed their travel through the rinsing apparatus, the cans are removed from the rinsing turret C and are delivered to a chain 14 which discharges them from the apparatus. See Figure 4. It will be understood that a description of the equipment at any one station is intended to apply as a description of all of the other stations.

Considering the illustrative embodiment in greater detail, power for operating all the parts may be supplied by an electric motor 15 mounted on the base 1 and being connected by a belt 16 to a pulley 17 fast on a shaft 18 journaled as at 19-19 in the casing 20 of a reduction gear unit 21 fixed as a whole with respect to the frame A. See Figures 1, 2, 4 and 7. The unit 21 includes a worm 22 shown in Figure 7 as being fast on the shaft 18 and meshing with a worm wheel 23 keyed to a vertical shaft 24 supported by a pedestal bearing 25 at the bottom of the casing 20 and journaled in the top of the casing 20 as at 26. (See Figure 2.) A spur gear 27 keyed to the

shaft 24 exteriorly of the casing 20 is in mesh with a spur gear 28 keyed to a vertical shaft 29 having its lower end supported and journaled by a pedestal bearing 30 carried by the base 1. For permitting timing adjustments to be made the gear 27 is formed to include a hub 27a and a toothed ring portion 27b adjustably secured to the hub by screws 27c. Similarly the gear 28 includes a hub 28a and a toothed ring portion 28b secured thereto by screws 28c. See Figure 2.

Fixed to the upper end of the shaft 29 is the lower half of an adjustable coupling 32, the upper half of which is keyed to a shaft extension 29a axially aligned with the shaft 29 and journaled in a frame carried bearing 33. The spur gear ring section 28b meshes with a spur gear 34 on the shaft 5 so as to drive the latter together with the turrets B and C and the spider D. See Figure 2.

Mechanism for feeding cans to the treating turret B may be of any suitable construction and in the form shown the feeding mechanism generally designated F includes a block chain 35 having an upper horizontal stretch extending from a sprocket 36 adjacent one side of the machine toward the center of the machine and over a sprocket 37. See Figures 1, 2, and 3. A tapered timing screw 38 of well known construction extends alongside the upper stretch of the chain 35 and is mounted for rotation by pintle bearings 39-39. Fixed guides 40 and 41 are provided adjacent the sprocket 36 for assuring that cans placed on the machine will be positioned over the chain 35. Cans moved by the chain 35 toward the right as viewed in Figure 3 are guided into contact with the timing screw 38 by a yieldable guide 42 pivoted as at 43 on the frame A.

A feed turret 44 formed with can-receiving pockets 44a is splined to the top of the shaft extension 29a and is so positioned as to receive cans from the timing screw 38 and deliver them to the treating turret B, a fixed arcuate guide 45 maintaining cans in the pockets 44a until the cans are delivered to the treating turret B.

The mechanism for driving the chain 35 and screw 38 in timed relation to the driving of the feed turret 44 (see Figures 1 and 2) includes a stub axle 46 mounted in a frame bracket 47, a bevel gear 48 rotatable on the shaft 46 and meshing with a bevel gear 49 keyed to the shaft extension 29a, and a sprocket 50 secured to the bevel gear 48 and having driving engagement with the block chain 35. The chain 35 extends downwardly from the sprocket 37 around and in engagement with the sprocket 50 and thence in engagement with an idler sprocket 51 which is journaled on an arm 52 pivoted on the frame as at 53 and being held in adjusted position as at 54, the arrangement being such that by adjusting the position of the arm 52 about the pivot 53, the desired tightness of the chains 35 can be obtained. After passing over the idler sprocket 51 the chain 35 extends to and drivingly engages a sprocket 55 fast with which is a gear 56 meshing with a gear 57 arranged to drive the timing screw 38 through a bevel gear couple 58. See Figure 1.

The treating turret B is provided with a set of circumferentially spaced tables 59 (see Figures 2 and 10) secured to the turret by screws 60, there being a table 59 at each treating station. Associated with the table 59 at each station is mechanism for carrying a can, raising it preparatory to the electrolysis treatment, and then lowering it. Each table 59 is formed with a central bore which receives and guides for vertical movements a stem 61 having secured to its upper end

a bronze can supporting or carrying pad element 62. Each can carrying pad 62 and associated stem 61 are held against rotation by a key 63 and are urged downwardly by a spring 64 interposed between the bottom of the table 59 and a washer 65 abutting a clevis head 66 on the lower end of the stem 61. Each clevis head is provided with a cam follower roller 67 which is urged into contact with a cam 68 extending concentrically around the main shaft 5. The contour of the cam 68 as shown developed in Figure 11 comprises a low portion 68a, a raising portion 68b, a high portion 68c, and a lowering portion 68d. The cam may conveniently be mounted on a bar 69 fixed with respect to the frame A. Mounted on top of each pad 62 is a semi-circular block 70 formed with an undercut groove 71 adapted to receive the seam joining a can body and can end so as to hold the can on the pad 62.

During the rotation of the treating turret B and just prior to introducing electrolyte into each can, the associated pad 62 is raised so as to bring the upper end of the can into engagement with a sealing device carried by the spider D, raising of the pad and supported can taking place when the associated roller 67 moves upwardly on the raising portion 68b of the cam 68. Directly above the can carrying pad 62 at each station is an overflow retaining cup element 72 which is carried by rods 73 and 74 both suspended from a measuring cup assembly 75 mounted on the spider D. Each rod 73 is fixed to a bracket 76 extending from the associated measuring cup assembly 75 and at its lower end is formed with a head 77 which has relative sliding engagement with an enlarged bore 78 formed in the overflow cup 72. The head 77 is engageable with the upper and lower ends of the enlarged bore 78 for fixing respectively the lower and upper limits of movement of the overflow cup 72. A spring 79 interposed between the overflow cup 72 and a collar 80 fixed to the rod 73 urges the overflow cup 72 toward the lower limit of its travel. The rod 74 is fixed to the overflow cup 72 and extends upwardly through and for relative sliding movements in a delivery pipe section 81 of the associated measuring cup assembly 75. A normally closed disk valve 82 secured to the upper end of the rod 74 is cooperable with a valve seat 82a for controlling communication between the measuring pocket 7 and the overflow cup 72. A spring 83 interposed between the bottom of the delivery pipe section 81 and a collar 84 fast on the rod 74 urges the rod 74 and the overflow cup 72 to their lower positions.

In operation when a pad 62 is raised by cooperation of the associated cam roller 67 with the raising portion 68b of the cam 68, the open upper end of the can X supported on the pad will be moved into engagement with a rubber sealing part 85 secured to the bottom of the associated overflow cup 72. The cup will then be raised against the urge of the spring 79 and 83, thereby lifting the valve disk 82 from its seat 82a, as shown in Figure 10, and permitting electrolyte contained in the associated measuring pocket 7 to flow downwardly through the delivery pipe section 81 into the overflow cup 72 and thence into the can. In order to assure that the can will be completely filled with electrolyte, the charge of electrolyte in each pocket 7 is measured to be of such quantity that the electrolyte will not only fill the can but will extend upwardly into the overflow cup 72 without, however, overflowing onto the outside surface of the can. Thus, the capacity of

each measuring container 7 is equal to the capacity of the can being treated plus at least a part of the capacity of the overflow cup 72.

As will be described hereinafter, means are provided for rejecting any can which has not been filled to overflow to a predetermined extent prior to the electrolysis treatment.

Mechanism carried by the spider D is provided at each station for lowering an electrode into the can being treated and for establishing an electric circuit through the electrode, the electrolyte, and the can. At each station an electrode carrier 86 is mounted above the respective can carrying pad 62 for vertical sliding movements in guides 87 and 88 supported on the spider D. Each electrode carrier 86 is equipped with a roller 89 which is cooperable with a cam 90 carried on the frame A and extending concentrically around the main shaft 5. As shown developed in Figure 11 the cam 90 includes a high portion 90a, a lowering portion 90b, a low portion 90c, and a raising portion 90d, the contour of the cam 90 being substantially the reverse of the contour of the cam 68. In order to prevent rotation of the electrode carriers 86 about their own axes, each is provided with a roller 91 guided for straight vertical movements in a groove 92 in the spider D. Preferably the electrodes 8 are detachably connected to the electrode carriers 86 so as to permit replacement of electrodes when necessary.

In operation cans, fed to the treating turret B by the block chain 35, the timing screw 38 and the feed turret 44 are placed successively on the treating turret pads 62 as the treating turret B revolves with the main shaft 5. Soon after each can leaves the feeding turret 44 the associated roller 67 moves upwardly on the raising portion 68b of the cam 68, causing the open end of the can to come into sealing contact with the rubber bottom facing 85 of the associated overflow cup 72, thereby raising the overflow cup, as shown in Figure 10. The valve 82 opens in response to the lifting of the can and overflow cup so as to cause electrolyte to be delivered to the can and overflow cup. At about this time the roller 89 carried by the associated electrode carrier 86 is moved downwardly by the lowering portion 90b of the cam groove 90 so as to project the electrode 8 into the can. Electrical connections to be described later then cause the current to flow through the electrolyte to effect the desired electrolysis treatment for approximately three seconds during which the cam rollers 67 and 89 are moving over the cam portions 68c and 90c respectively. When the treatment has been completed, the cam roller 67 will move down the lowering portion 68d of the cam 68 to lower the can away from the overflow cup and at about the same time the cam roller 89 will move up the raising portion 90d of the cam groove 90 so as to elevate the electrode carrier 86 and move the electrode 8 completely out of the can.

After the treatment of the cans has been completed, they are removed from the treating turret and fed past the rejecting wheel 10 and if not rejected thereby are delivered to the rinsing or washing turret C. In the form shown, the cans are deflected from the treating turret B by an arcuate guide 93 secured to the frame A and positioned to direct the cans into the pockets 94a of a transfer turret 94 which feeds the cans onto the chain 9 previously referred to. The chain 9 trained around sprocket wheels 95, 96, 97 and 98 journaled on the frame A to rotate about horizontal axes (see Figure 1), includes a plurality of

articulated plate sections 99 secured to each of which is a semicircular block 100 formed with an undercut groove 101 (see Figure 6), adapted to receive the can end seam. The top horizontal stretch of the chain 9 between the sprockets 95 and 96 moves to the right as viewed in Figures 1 and 3 so as to feed the cans past the rejection wheel 10 which is mounted on a shaft 102 supported in a bearing bracket 103 carried by the main frame A. See Figure 1.

If any can has not been given the proper treatment during its movement around with the treating turret B, mechanism to be described later will turn the shaft 102 and the rejection wheel 10 when that particular can reaches the rejection wheel, so as to displace the can from the chain plate 99 and move the can into a chute 104. Cans not so rejected will continue to move with the chain 9, being held against displacement from the plates 99 by the blocks 100 and a side guide 105 (see Figures 1 and 5). As the cans pass over and around the sprocket 96, the electrolyte will be dumped from the cans into a catch basin 106 (see Figure 5) from which the electrolyte is re-circulated for further use as will be described later. After passing around the sprocket 96, the cans will be carried in inverted position by the blocks 100 past the sprocket 97 and thence over a frame carried shelf 106a on top of which is mounted an arcuate guide 107. The guide 107 displaces the cans from the blocks 100 on the chain plates 99 so as to permit the cans to drop to the shelf 106a and to be received in pockets 108a of a transfer turret 108. See Figure 4. The turret 108 then feeds the cans over the shelf 106a and to a guide 109 which directs the cans into pockets 110a of another transfer turret 110. The turret 110 feeds the cans beyond the guide 109, off the shelf 106a and into pockets 111 on the rinsing turret C, rotation of which carries the cans in inverted position over the spaced tracks 11-11. While being moved around on the tracks 11-11 by the treating turret C, the cans are subjected to sprays of rinsing liquid from the upper pipes 12 and lower spray nozzles 13. This effectively cleanses the cans of all electrolyte which may have adhered to the cans after their inversion while passing around the sprocket 96.

Referring more particularly to the mounting and driving of the transfer turret 94, the chain 9 and the transfer turrets 108 and 110, the plate sections 99 of the chain 9 are provided with inner rollers 112 (see Figures 5 and 6) which are engageable with the toothed peripheries of the sprockets 95, 96, 97 and 98. The rollers 112 are adapted to ride over a trackway 113 carried by the frame A and extending under the upper stretch of the chain between the sprockets 95 and 96 so as to prevent sagging of the chain. The chain plate sections 99 also are provided with outer rollers 114 adapted to roll upon a frame carried trackway 115 underlying the lower stretch of the chain between the sprockets 96 and 97. See Figures 1 and 5. Rollers 116 mounted on the outer ends of the chain plate sections 99 cooperate with a frame carried groove track 117 to hold the chain plates against tipping under the weight of the cans. Guard plates 99a secured to the plates 99 prevent electrolyte from running onto the rollers 112, 114 and 116.

The transfer turret 94 is secured to the upper end of a shaft 118 which is journaled at its lower end in a pedestal bearing 119 and at its upper

end in a bearing 120 (see Figure 6). The shaft 118 is provided adjacent its lower end with a spur gear 121 comprising a hub 121a keyed to the shaft 118 and a toothed ring section 121b adjustably secured to the hub by screws 121c. The ring section 121b meshes with the spur gear 34 carried by the main shaft 5, and thus the shaft 118 and transfer turret 94 are driven in timed relation to movement of the cans by the shaft 5 and treating turret B.

For driving the chain 9, the sprocket 96 has fast therewith another sprocket 122 over which is trained a chain 123 which passes around a drive sprocket 124 and in engagement with a chain tightener idler sprocket 125 adjustably mounted on the frame A. The drive sprocket 124 is secured to a shaft 126 journaled on a frame mounted bracket 127, the shaft 126 being provided with a bevel gear 128 which meshes with a bevel gear 129 keyed to the shaft 118. The transfer turret 108 is secured to the top end of the shaft 24 which is driven by the reduction gear unit 21 as previously described. See Figures 2 and 4. The companion transfer turret 110 is secured by a bolt 130 and dowel 131 to a collar 132 keyed on the shaft 29.

After passing through the washing equipment the cans are moved off the tracks 11-11 and onto a shelf 133 (see Figures 1 and 4) supported on the frame A. An arcuate guide 134 which receives the cans from the pockets 111 of the washing turret C directs the cans into the pockets 135a of a transfer turret 135 fixed to a shaft 135b fast with which is a gear 135c meshing with an idler gear 135d which in turn meshes with a gear 135e on the shaft 118 (see Figures 1, 3, 4 and 6). The turret 135 moves the cans onto the discharging chain 14 which is trained over sprockets 136 and 137 and a tightener sprocket 138 mounted on a frame standard 139 supported by the frame A. Stationary guides 140 adjustably secured to the standard 139 as at 141 prevent the cans from being accidentally displaced from the discharging chain 14. For driving the chain 14 the sprocket 137 is fast on a shaft 142 journaled on the frame standard 139, the shaft 142 having fast therewith a sprocket 143 over which is trained a chain 144 which passes around a sprocket 145 fast on the shaft 145' which carries the sprocket 96 previously referred to (see Figures 1, 3 and 5). A tightener sprocket 146 is adapted to adjustably tension the chain 144.

When the cans have passed with the chain 14 to the discharge end thereof at or over the sprocket 137, they have completed their travel through the machine and may then be taken to a steam chamber and then to a drier (not shown).

Electrolyte is supplied to the measuring pockets 7 as they pass from the point at which cans are removed from the treating turret B to the point at which other untreated cans are fed to the treating turret. In the form shown, an electrolyte supply pipe 147 discharges through a fan-shaped nozzle 148 adjacent the top portion of the apparatus, the electrolyte falling from the nozzle 148 into the pockets 7 (see Figures 1 and 8). A shrouding ring 149 (see Figures 2 and 10) is carried by the spider D outwardly beyond the pockets 7 and extends above the tops of the pockets for preventing electrolyte from splashing onto the electrode carriers 86 and associated electric and detector mechanism to be described later. Preferably the pockets 7 are fitted with removable displacement liner inserts 150 which are adapted

to be removed and replaced by liners of greater or lesser displacement so as to decrease or increase the net resultant capacity of the measuring pockets to thereby provide for regulation of the size of electrolyte charge in accordance with the size of cans being treated. The electrolyte is delivered from the nozzle 148 at such a rate that the pockets 7 will be filled to overflowing, the overflow electrolyte descending into a catch basin 151 formed as part of the spider D and thence through a down pipe 152 which discharges into a catch basin 153 formed as part of the frame A. The electrolyte is then discharged from the catch basin 153 through a drain pipe 154. See Figures 2 and 5. In order that the cam 68 and rollers 67 may not be splattered with electrolyte, the turret B is formed with depending splash guards 155 which overlap upstanding splash guards 156 mounted on the cam supporting part 69. See Figure 10. Electrolyte contained in rejected cans moved off the chain 98 by the rejection wheel 10 will be drained from the chute 104 through a pipe 154a. See Figure 5.

The electrolyte discharged from the treating apparatus through the pipes 154 and 154a is recirculated and new electrolyte is added to compensate for the small amount of the electrolyte that is consumed during the treatment or that adheres to cans and is carried into the washing zone. Figure 12 shows diagrammatically a preferred arrangement of electrolyte circulating and make-up system. The main supply of electrolyte is maintained at a temperature of 68° F. in a cooler and storage tank 157 which discharges through a pipe 158 to a pump 159, which in turn delivers electrolyte into the feed pipe 147 hereinafter referred to, a manually operable cut-off valve 160 preferably being interposed in the pipe 147. A valve 161 interposed in the pipe 147 adjacent the nozzle 148 may be controlled manually or by a solenoid 161' mounted on the frame A. See Figure 1. Fluid drained off through the pipes 154 and 154a is led to a pipe 162 which extends from the bottom of the catch basin 106 to a pipe 163 vented at 164 and thence to a sump 165. Electrolyte flows from the sump through the pipe 166 and a check valve 167 to a pump 168 which delivers electrolyte through a pipe 169 and valve 170 back to the cooler and storage tank 157, thus completing the circuit. For making up or supplying electrolyte to take the place of that consumed in the treating process or carried into the washing zone by adhering to the cans, a prepared supply of electrolyte is maintained in a tank 171 arranged to deliver electrolyte through a pipe 172 to a settling tank 173. Preferably this delivery is effected by maintaining fluid in the mixing tank 171 under sufficient pressure to lift the electrolyte through the pipe 172. Electrolyte can flow by gravity from the settling tank through a pipe 174 controlled by a valve 175 to the cooler and storage tank 157. The tank 157 may be vented by a pipe 176 which opens into the settling tank.

Water for rinsing or washing adhering electrolyte from the cans in the washing zone is delivered to the spray pipes 12 and 13 through a supply pipe 177 controlled by a master valve 178 (see Figures 2 and 4). A branch pipe 179 controlled by a valve 180 leads from the pipe 177 to the upper spray pipes 12. Branch pipes 181 and 182 equipped respectively with valves 183 and 184 deliver water to the lower spray nozzles 13. Water sprayed from the pipes 12 and nozzles 13 will impinge upon and thoroughly cleanse the outside

11

and inside surfaces of the cans while they are being moved around by the rinsing turret C. The washing water falling from the cans will be collected on the base of the frame A from which it is drained through a pipe 185 which may lead to a sewer.

Referring now to Figures 9, 11 and 13 which show diagrammatically the means for supplying current to effect electrolysis of the cans and for detecting and rejecting any cans which may be imperfectly treated, a motor 186 supplied with power from a three wire line 187 is arranged to drive a direct current generator 188. Current is delivered by the generator 188 through conductors 189 and 190 and a main cut-off switch 191 to conductors 192 and 193 which are connected respectively to live sectors of an outside fixed collector ring assembly generally designated 194 and an inside fixed collector ring assembly 195, both ring assemblies being mounted upon but electrically insulated from the frame A. The collector ring assembly 194 comprises sectors 194a, 194b, 194c, and 194d and the collector ring assembly 195 includes similar sectors 195a, 195b, 195c, and 195d. The sectors 194c, 194d, 195c and 195d are dead, that is, are not connected to the current supply lines 192 and 193. The supply conductor 192 is directly connected to the ring sector 194a of the outside collector ring assembly which in turn is connected through a conductor 196 to the sector 195b of the inside ring assembly. Similarly the supply conductor 193 is connected to the sector 195a of the inside ring assembly which in turn is connected through a conductor 197 to the sector 194b of the outside ring assembly. The arrangement is such that the sectors 194a and 195b are of negative polarity and the sectors 195a and 194b are of positive polarity.

For establishing a circuit through the electrodes, the electrolyte and the cans, each electrode carrier 86 and associated can carrying pad 62 is connected to brushes 198 and 199 (see Figures 3, 10 and 13) adapted respectively to travel over the collector ring assemblies 194 and 195. In the embodiment shown, the electrolysis circuit includes the brush 199 contacting the inside ring assembly, a conductor 200 leading from the brush 199 to the electrode 8, the electrolyte in the can, the can itself, the can supporting pad 62, a conductor 201, a fuse 202 interposed in the conductor 201, a relay coil 203, a conductor 204, and a conductor 205 which leads to the brush 198 in contact with the outside ring assembly 194. The equipment carried by the spider D at each station includes brushes 198 and 199, conductors 200, 201, and 205, a fuse 202, and a relay coil 203.

In operation each can supporting pad 62 is rotated in the direction of the arrow R (see Figure 13) and after the associated can has been filled with electrolyte and the associated electrode 8 has been lowered, the brushes 198 and 199 will move respectively into contact with the ring sectors 194b and 195b, establishing an electric circuit through the can and electrolyte with the can serving as the anode and with the electrode 8 serving as the cathode. The circuit will be thus maintained while the brushes 198 and 199 are traveling over the relatively short sectors 194b and 195b which may be for a period of about one half second. When the brushes pass into contact with the longer ring sectors 194a and 195a the circuit will be reversed so as to make the can act as the cathode and the electrode 8 act as the anode. The circuit as thus reversed will be maintained operative until the brushes 198 and 199

12

have completed their travel over the relatively long ring sectors 194d and 195d requiring approximately two and one half seconds. The brushes will then move onto the dead ring sectors 194c and 195c and the circuit will be broken. Thus the electrolysis treatment is carried on for approximately three seconds, the polarity being changed after about the first one half second of the treatment.

If the electrolysis treatment given any particular can is not carried out properly, it is desirable that the can be rejected rather than to be delivered with other cans which have been treated properly. One possible cause for failure of the electrolysis treatment would be the insufficient or incomplete filling of the can with electrolyte. In accordance with the invention, detecting equipment is provided for causing the rejection wheel 10 to remove from the chain 9 any can which was not completely filled with electrolyte when the electrolysis treatment was performed. In the form shown, the overflow cup 72 at each station is equipped with a contact 206 adapted to project into electrolyte extending upwardly from a properly filled can into the overflow cup. A conductor 207 leading from the contact 206 is connected to a fuse 208 in turn connected through a conductor 209 to a relay coil 210 which is connected through a conductor 211 to the conductor 205 which leads to the brush 198 contacting the outside ring assembly 194a. The electrode 8 is connected through the conductor 200 to the brush 199 contacting the inside ring 195. If there is no electrolyte at the level of the contact 206, the control circuit will be broken between the contact 206 and the electrode 8 so that the relay coil 210 will be deenergized, thus closing the normally open contactor 212. When the contactor 212 is closed, a circuit is completed through the winding 213 of a solenoid 214, the circuit beginning at the inside ring 195, thence to the brush 199, the conductor 200, a conductor 215, the contactor 212, a conductor 217, the solenoid winding 213 and a conductor 218 leading from the solenoid winding to a trailing brush 219 arranged to make contact with one of a plurality of contact segments 220 projecting from the outside ring assembly 194.

Energizing of the solenoid will effect raising of a solenoid plunger 221 so as to condition it for cooperation with a toothed wheel 222 mounted on a shaft 223 journaled on the frame bracket 103. When the solenoid plunger 221 is raised, it will remain in raised position while the solenoid and plunger are moved around with the spider D until the plunger engages a tooth on the wheel 222 and imparts a step rotary movement to the wheel. Rotation of the wheel 222 is transmitted through the shaft 223, bevel gears 224, a shaft 225, and a sprocket and chain drive 225a to the shaft 102 on which the rejection wheel 10 is mounted. See Figure 1.

The solenoid electrically and functionally associated with each station is physically located six stations behind the particular station in connection with which it functions. The arrangement is such that if the electrolyte at any treating station fails to rise and engage the contact 206, the solenoid plunger at the sixth station behind that treating station will be projected but it will not engage the wheel 222 until after the improperly treated can has had time to be moved off the treating turret B, around with the transfer turret 94, onto the chain 9, and to a position in the plane of the rejection wheel 10. Thus at the

time a can is being treated with insufficient electrolyte, the associated solenoid plunger 221 is conditioned to bring about rejection of that can, but the actual operation of the rejecting wheel 10 is not effected until the can has completed its travel with the treating turret and has been moved up to the rejection station.

It would be possible for the electrolysis circuit to fail due, for example, to a loose connection or broken conductor even though electrolyte has been filled to the proper overflow level in the can and overflow cup 12. Means are provided at each station for detecting any such failure of the electrolysis circuit and for bringing about the rejection of any can which, due to such failure, has not been given the proper treatment. In the form shown, each detecting means includes the relay coil 203 previously referred to and which forms part of the circuit through which the electrolysis current must pass. If the electrolysis circuit should be broken, the relay coil 203 will be de-energized to bring about closing of a normally open contactor 226 which in turn will bring about the completion of a control circuit through the solenoid winding 213. See Figure 13. Beginning with the inside ring assembly 195 this control circuit would include the inside brush 199, conductors 200, 215 and 227, the closed contactor 226, the conductor 217, the solenoid winding 213, the conductor 218, the trailing brush 219, and a segment 220 projecting from the outside ring 194. Thus the associated solenoid plunger 221 would be raised into position for delayed cooperation with the wheel 222 to operate the rejection wheel 10 in the manner previously described.

It has been found undesirable for the trailing brush 219 to make direct contact with the extended segments 194b or 194a because this would create an electrical current which would cause the cans to be discharged. It is for this reason that the projecting segment portions 220 are provided for being contacted at intervals by the trailing brush 219.

It will be understood that the plunger 221 contacts with the wheel 222 in the same manner irrespective of whether it was raised because of an insufficient charge of electrolyte or because of breaking of the electrolysis circuit in some other way. After a raised plunger 221 is moved beyond the wheel 222, it will engage a cam 228 fixed to the frame A so as to be pushed back down to its lower position.

Any suitable means may be provided for cutting off the motor 15 to stop the machine in the event of abnormal resistance to rotation of the shaft 5 and the associated driven parts. In the form shown, means for so stopping the machine include a spring 229 interposed between an adjustable abutment 230 and one thrust bearing 19 which journals the worm 22 in the drive unit 21. The spring 229 is under compression so as normally to oppose the thrust of the worm 22 and maintain the latter in the position shown in Figure 7. In the event of an abnormal load due, for example, to jamming of the machine, a higher than normal thrust would be exerted upon the worm 22 causing it to be moved axially against the yieldable spring 229. Axial movement of the shaft 18 and pulley 17 together with the worm 22 will cause the pulley to rock a lever 231 and effect operation of a micro-switch 232 arranged in any desired manner to break the circuit to the motor 15.

The machine for treating cans and for cooling and supplying the electrolyte is operated by four

motors, viz. the motor 186 driving the generator 188, the machine motor 15 and two motors for driving the pumps 159 and 168 respectively. The motors, the means for establishing the electrolysis circuit and the detector controls are all connected in a control circuit shown diagrammatically in Figure 13. The operation of the motors is controlled from starters and a control relay located in a central cabinet in turn controlled by start-stop push button stations and a selector switch. The electrical controls are so arranged that the machine may be operated selectively under either an automatic cycle during normal running of the machine or a manual cycle for test and set up purposes.

With the selector switch in the automatic position it is necessary that the generator be operating before the pumps can operate. Operation of the motor generator starter causes the pumps 159 and 168 to be started by means of an additional normally open interlock contact. With the motor generator 186-188 and the pumps 159 and 168 operating, it is possible to commence operation of the machine motor 15 providing the clutch overload limit switch control circuit is closed. The machine motor 15 may be started and stopped from its own start and stop bases.

An additional normally open interlock on the supply pump starter is in series with the machine motor control and is so interlocked that the supply pump 159 and the generator 188 must be running before it is possible to operate the machine motor 15. The discharge circulating pump 168 is started and stopped by means of a high and low level float switch 233 on the sump tank. See Figure 13. This control circuit is energized by means of a normally open relay which in turn is energized by the CR relay or the push button in the cover of the cabinet.

The overload relays on all four motor starters are connected in series in the common control line so that tripping of any overloads in the common control line will automatically shut down the entire equipment. The motors all operate on 440 volts, 3 phase, 60 cycle, but the control circuit of the motor starters and push button units are supplied with current at 110 volts taken from the control circuit transformer.

Prior to placing the apparatus in continuous operation it may be desirable to operate it under the manual cycle for test or set up purposes. To effect such operation, the selector switch is turned from automatic position to manual position causing the control relay CR to operate. The relay CR has three normally open and two normally closed contacts. The two normally closed contacts which were in the two pump motor starters, open to keep the pumps from starting when the motor generator is started. This allows for starting of the pumps by means of their own start and stop stations. The pump starters have their own circuit interlocks which make for three wire control of the pump motors. One of the normally open contacts on the control relay CR establishes a circuit from the master stop station to the control circuit for the pumps as well as the machine motor 15. Thus even though the motor generator 186-188 is not operating, it is possible to start any or all of the three units by their own separate start and stop stations.

Another of the normally open poles of the relay CR is used to bridge the interlock circuits so that the machine motor may be started irrespective of whether the pump is operating or not. The fifth and last contact which is normally open

15

on the relay CR is employed for energizing two pilot lights, one of which is located in the control station at the operator's point and the other of which is located at the top of the control cabinet itself. The latter pilot light preferably is red and is for notifying the operator that the panel is set up for a manual operating cycle.

In the door of the A. C. control cabinet are three sets of start and stop stations which are intended for operating the motor generator set and pumps for manual operation.

In a control station mounted at the operator's position at the machine is a control station consisting of a manual or automatic position selector switch for cycle selection, a pilot light to indicate to the operator when the manual cycle has been selected, a start button, and a stop button for control of the machine motor 15. The control station also includes an inch-run selector switch by which the machine motor control may be set up for inching purposes. Also provided is a master stop button with a mushroom cap which when operated will shut down the entire machine. A keyed switch in the control circuit for the machine motor 15 provides for locking the machine against being started by any unauthorized person.

The control panel has in addition to the parts and control devices referred to a main disconnect switch, a three pole fuse block for use on small motors, a two pole fuse block for protecting the control circuit, and a control circuit transformer.

Before starting operation, the "Inch-Run" and "Auto-Hand" switches on the control station 234 should be at the "Run" and "Auto" positions respectively. If the "Auto-Hand" switch is at the "Hand" position, one red light will show on the cover of the control station 234 and on top of the A. C. control panel. See Figure 1. In the cover of the A. C. control panel 235 there are three sets of start-stop buttons, one set being for the motor generator and one set each for the pumps. The start button for the motor generator is then pushed. Then the handle on the rheostat 236 on the control panel is turned to the right or left as required to bring the voltage to 55. After the treating section of the machine has a can at each station the voltage should be rechecked and such adjustments made as may be necessary to bring the voltage to 55.

With the motor generator running and the voltage set at 55 as described above, the wash water valve 178 should be opened and the D. C. switch 191 should be closed. It then will be possible to start the machine by pushing the start button on the control station 234.

The apparatus described and claimed herein embodies the invention in the form now preferred, but it will be understood that changes may be made without departing from the invention as defined in the claims.

We claim:

1. In a machine of the character described, a frame, a turret rotatable thereon, a plurality of can supports circumferentially spaced around said turret, means mounting said supports for vertical movements on said turret, a plurality of open bottom overflow cups, means mounting said overflow cups respectively above said can supports to move around with said supports and to move vertically toward and away from said supports, a plurality of measuring containers mounted respectively above said overflow cups, valves for controlling communication between said measuring containers and their respectively

16

associated overflow cups, a plurality of electrodes mounted for vertical movements respectively above said overflow cups, cam means on said frame, cam follower means associated with said can supports, said valves and said electrodes for cooperation with said cams during rotation of said turret for raising the can supports to bring the open ends of cans supported thereon into sealing engagement with the associated overflow cups, opening said valves to discharge electrolyte from said measuring containers into said overflow cups and said cans, and moving said electrodes down into the electrolyte in said cans, and means for establishing an electric circuit through said electrodes, said cans, and the electrolyte therein.

2. In a machine of the character described, a vertical shaft, a treating turret fixed to said shaft, means for feeding cans to circumferentially spaced stations on said treating turret, a member fixed to said shaft above said treating turret, a plurality of measuring containers carried by said member and positioned respectively to discharge electrolyte into cans at said turret stations, means for delivering electrolyte into said containers, valves respectively controlling the discharge of fluid from said containers, a plurality of electrodes movably mounted on said member respectively above said turret stations, a fixed cam, cam follower means engageable with said cam for opening said valves to permit discharge of fluid into the cans and to then effect closing of the valves after the can treatment, a second fixed cam, cam follower means engageable therewith for moving said electrodes into the cans and then withdrawing the electrodes after the can treatment, and means for establishing electric circuits through said electrodes, the respectively associated cans, and the electrolyte contained therein.

3. In a machine of the character described, means for feeding cans to be treated and delivering treated cans at a discharge point, means for applying and maintaining electrolyte in contact with the inside surfaces of the cans being fed, electrode means, means for effecting relative movement of the cans and said electrode means to position the electrodes in the electrolyte, means operable when each can is at an intermediate point of its feeding movement for establishing an electric circuit through said electrode means, the can being treated, and the contained electrolyte, a rejector device for displacing cans from said feeding means at a point removed from the point at which treatment is effected, normally inoperative means for actuating said rejector device, detector means responsive to failure of said electric circuit to be closed through any given can being treated for conditioning said actuating means to operate said rejector device, and means timed with respect to can feeding for bringing said actuating means into operation to actuate said rejector device and displace said any given can from the feeding means.

4. In a machine of the character described, a supporting frame, a turret mounted therein for rotation about a vertical axis, a plurality of can treating units circumferentially spaced around said turret, each unit including a can support mounted for vertical movement on said turret, an overflow cup mounted above the can support for limited vertical movement toward and away from the support, a measuring container mounted on said turret above said overflow cup, a valve for

controlling communication between the measuring container and the associated overflow cup, an electrode mounted for vertical movement above the overflow cup, cam means on said frame and cam followers associated with the cam support and the electrode for cooperation with said cams during the rotation of the turret for raising the can support to bring the open end of the can supported thereon into sealing engagement with the associated overflow cup, for operating said valve to discharge electrolyte from the measuring container into the overflow cup and the can and for moving the electrode into the electrolyte in the can, and means for establishing an electric current through the electrode, the can and the electrolyte therein.

5. In a machine of the character described, a supporting frame, a turret mounted therein for rotation about a vertical axis, a plurality of can treating units circumferentially spaced around said turret, each unit including a can support mounted for vertical movement on said turret, an overflow cup mounted above the can support for limited vertical movement toward and away from the support, said overflow cup having a sealing gasket attached to the under face thereof adapted to be contacted with by the open end of the can, means for raising the can support controlled by the rotation of the turret for causing the can to engage said cup and raise the cup after making sealing contact therewith, a measuring container mounted on the turret above said overflow cup, a valve for controlling communication between the measuring container and the overflow cup, said valve being operated by the raising of the overflow cup, an electrode mounted for vertical movement above the overflow cup, and means operated by the rotation of the turret for moving the electrode into and out of the container, and means for establishing an electric circuit through the electrode, the can and an electrolyte therein.

6. In a machine of the character described, a supporting frame, a turret mounted therein for rotation about a vertical axis, a plurality of can treating units circumferentially spaced around said turret, each unit including a can support mounted for vertical movement on said turret, an overflow cup mounted above the can support for limited vertical movement toward and away from the support, a spring for moving said cup to its lower limited position, means operated during the rotation of the turret for raising the can support for causing a can mounted thereon to make sealed contact with the lower face of the overflow cup and raise said cup, a measuring container mounted on said turret above said overflow cup, a valve for controlling communication between the measuring container and the associated overflow cup, said valve being operated by the raising of the overflow cup, means operated during the rotation of the turret for supplying the measuring container with an electrolyte which is discharged when the valve is open into the can and overflow cup, an electrode

mounted for vertical movement above the overflow cup, means operated during the rotation of the turret for moving the electrode into and out of the electrolyte, and means for establishing electric circuit through the electrode, the can and the electrolyte therein.

7. In a machine of the character described, a supporting frame, a turret mounted therein for rotation about a vertical axis, a plurality of can treating units circumferentially spaced around said turret, each unit including a can support mounted for vertical movement on the turret, an overflow cup mounted above the support, a measuring container mounted on the turret above the overflow cup, a valve for controlling communication between the measuring container and the associated overflow cup, an electrode mounted for vertical movement above the overflow cup, cam means on the frame and cam followers associated with the can support and the electrode for cooperation with said cams during the rotation of the turret for raising the can support to bring the can into sealing engagement with the overflow cup for operating the valve to discharge the electrolyte from the measuring container into the overflow cup and for moving the electrode into the electrolyte in the can, and means for establishing and maintaining effective for a predetermined time electric circuit through the electrode, the electrolyte and the can, and for then reversing the polarity of the circuit and maintaining the circuit effective with reverse polarity for a predetermined time.
